WILLIAM F. ZIMMERMANN, OF MAPLEWOOD, NEW JERSEY, ASSIGNOR TO GOULD & EBERHARDT, OF NEWARK, NEW JERSEY, A CORPORATION OF NEW JERSEY

CAM CONTROLLED SHAPER FEED

Application filed June 10, 1927. Serial No. 197,797.

This invention is directed to step-feed mechanisms for machine tools, such as shapers, and it seeks in a simple way to attain a superior relationship between the cycles of 5 the reciprocating ram and the cycles of the intermittent feed; improving upon the nature and relative timing of the feed cycles.

In such machines, the length of stroke of the ram requires to be adjustable; according 10 to whether the work requires a long cut or a short cut. So also, the "feed" must admit of adjustment to regulate the depth of cut taken by the tool during each cutting advance thereof. It is desirable that no feed shall 15 ever take place during the cutting advance of the tool; otherwise the line of cut will depart from the actual path of the tool. The feeding movement should begin and end during the time the tool is non-functional and 20 this condition should not be disturbed by any adjustments in the length of the strokes either of the tool or of the feed which shifts the work. To achieve this result without involving mechanical complication is one of the 25 goals of this invention.

It is noteworthy, likewise, that the return or non-functional stroke of the tool is habitually made more rapidly than its advance. Also that its slow advance somewhat over- 30 runs the work, and its quick return carries the tool to a starting point located somewhat away from the work. In other words, the cycle of the tool is not uniform, and the point of time consumed for each entire non-uniform 35 cycle will likewise be of a longer or shorter duration; depending upon the length of the ram stroke and its selected rate of cutting determined by the setting of the speed change gears for the bull-wheel.

40 The starting and stopping instants of the "feed" for the work should be compatible with all of those selective conditions and should not take place while the tool is exercising its tooling office.

45 To utilize the shorter-arc period of the ram's return for accomplishing the feed-stroke, and for compensating for the difference of time consumed between the fast return and the slow advance of the ram, this 50 invention proposes a feeding cam having a

properly synchronized movement; as much or as little of which may next be appropriated (under the control of a limiting cam) to afford the amount of feed best adapted for the work in hand. This second or qualifying means is, by this invention, so conceived that it admits of being readily and accurately adjusted; its hand grasp being normally quite free from motion, even while the machine is running.

55 There should be neither skippage nor shortage in the feed strokes. To meet this desideratum, a unique construction has been developed. The feeding is periodically accomplished by the feeding cam, and the restoration of the ratchet means is self-actuating; the feeding cam then operating to restrain the rate, but not the extent, of its restoration. The latter is determined by the limiting cam which, at the station selected 60 by the feed adjustment, prohibits the feeding mechanism from further following the feeding cam.

65 Other objects and advantages will be in part indicated in the following description 70 and in part rendered apparent therefrom in connection with the annexed drawings.

To enable others skilled in the art so fully to apprehend the underlying features hereof that they may embody the same in the 75 various ways contemplated by this invention, drawings depicting a preferred typical construction have been annexed as a part of this disclosure and, in such drawings, like characters of reference denote corresponding 80 parts throughout all the views, of which:—

85 Figure 1 represents a side elevation of a shaper embodying this invention. Fig. 2 is an enlarged side elevation of the feed mechanism leading from the side of the column to 90 the table of the shaper. Fig. 3 is a horizontal section showing certain of the interior elements of the assembled feed mechanism. Fig. 4 is a vertical section through line 4—4 95 of Fig. 2 and Fig. 5 is a vertical section through line 5—5 of Fig. 3; showing details of the cams and elements related thereto. Fig. 6 is a vertical section through line 6—6 100 of Fig. 1 looking towards the right.

Upon the bed or column A of the machine

is arranged a ram B adapted to be reciprocated with a slow advance and rapid return, by means of any conventional mechanism such as the slotted link C actuated by a pin 5 D which is driven by a bull wheel E which, in turn, derives motion from a shaft F through appropriate change gears G. These elements, being conventional, are well known and require no detailed description.

10 The front face of the body A carries a conventional table and cross rail (indicated generally by H) and as such features of construction are likewise conventional and well known they will not be detailed.

15 The intermittent feed for the table is derived from a continuous rotary motion of a sleeve 1 which rotates with the bull wheel. Coaxially secured to this sleeve (as through the plate 2) is a positively driven feeding cam 3. This cam bears a fixed relationship to the bull wheel and its contour, as indicated by Fig. 5, and is so proportioned to the times and the rates of advance and retreat of the ram B (the strokes of which are adjusted by adjusting the position of the pin 15 D) that the advancements of the table will begin and end during non-functional periods of the tool.

Arranged to pivot coaxially with the feeding cam 3, is a limiting cam 4 which is keyed to an external hand grasp 5 or otherwise connected to some suitable means carrying a scale of graduations 6 which are available for indicating the manual setting of the limiting cam 4. An appropriate detent 7 intervenes between the hand grasp and a suitable casing 8 which will be subsequently described. This casing, as shown by Fig. 5, has a guide-way 9 directed substantially towards the axis of rotation of the feeding cam 3 and, arranged to reciprocate in said guide 9, is a plunger 10 having a rounded extremity 11 of sufficient width to be operated upon by whichever portions of either cams 3 or 4 happen to be in 20 suitable angular position for that purpose. Were it not for the limiting cam 4, the feeding cam 3 would periodically advance the plunger 10 from the same rearmost position to the same foremost position, and would permit an expansile spring 12 (restrained by the cap 13) to cause the plunger 10 to retreat from its foremost to its rearmost position, keeping it in contact with the receding portions of the feeding cam 3. This would yield an intermittent maximum feed. If the cam 4 be a duplicate of the feeding cam in size, proportion and mounting, and if it coincides with the feeding cam peripherally (as indicated by Fig. 6) then its effect will be negligible and the maximum feed will result. If the limiting cam 4 be set manually so as to occupy the position shown, for example by Fig. 5, then the plunger 10 obviously cannot retreat under the impulsive action of the spring 12 any further than after it has con-

tacted with the stationary cam 4. In other words, its selected limit of retreat is that shown in full lines as against the position indicated in dotted lines to which it could retreat were it not for the obstruction offered by the cam 4. The significance of this is that when the feeding cam 3 now rotates until it contacts with the end of the plunger, it is able to advance it only through the distance between the dotted lines *r* and *a* indicated by Fig. 5. The dotted line *a* represents an invariable station, and the dotted line *r* represents a selected station determined by the adopted position of the stationary cam 4. This means that the plunger 10 will have shorter or longer periodic strokes depending entirely upon the position of the limiting cam 4.

The intermittent reciprocations of the plunger 10, which, as has been seen, are truly synchronized with the ram, or converted into an intermittent forward rotation by means of a suitable one-way transmitter represented by K. This consists of a stub shaft 14 upon which is keyed a ratchet wheel 15 and upon which is sleeved an oscillator 16 driven by a gear 17 meshing with corresponding teeth 18 on the plunger and carrying a pin 19 upon which rocks a pawl 20; this pawl being always maintained in mesh with the ratchet teeth on the wheel 15 by reason of the continuous pressure of a spring pressed 21. The advantage of this is that the pawl is always conditioned to be immediately responsive to any advance of the plunger 10 and no irregularity in the feed can possibly occur. To prohibit any tendency of the pawl 20 to pull the ratchet wheel backwards by friction, a pair of stop pawls 22 and 23 are always held spring pressed in engagement with the ratchet wheel and prohibit any retrograde rotation thereof.

It is seen that the stub shaft 14 is given an intermittent forward rotation and, as the foregoing mechanism is all limited very excessively to the user at the side of the column A near the bull wheel, provision is made for conveying this motion to the table. A bevel gear 24 imparts the rotation of the shaft 14 to another bevel gear 25 at the end of a sleeve 26 which telescopically receives the splined end portion of a shaft 27 which terminates in a coned head 28 at its forward end. A bevel gear 29 loosely encircling the shaft 27 has a counter-coned socket which is spring pressed against the cone 28 by a spring 30. This causes the bevel gear 29 to rotate as a unit with the shaft 27 except in the event of exceptional strains during which slippage may take place. The bevel gear 29 is simultaneously in mesh with reversing bevel gears 31 and 32 which, by means of the usual clutch sleeve 33 may be used to drive the screw shaft 34 which intermittently feeds the table 4. To protect the running shafts a casing 35 is pivoted

coaxially about the shaft 34 and telescopes with a casing 36 which likewise pivots coaxially with the shaft 14; this arrangement accommodating the rise and fall of the cross rail on the front of the machine.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:—

1. A feed mechanism for machine tools embodying a work-holder, a tool-holder and means to effect relative reciprocation between the two combining a one-way motion transmitter; a positively impelled but impotively restored actuator operative tangentially thereto; a periodically acting energizer for positively impelling said actuator to drive said transmitter positively; and an adjustable limiter arranged coaxially with said energizer for controlling the extent of restoration of said actuator, said energizer and limiter both being adapted to act upon a common portion of said actuator.

2. A shaper combining a ram; an adjustable-stroke reciprocator therefor; a table; a table-feeding transmission; a one-way motion transmitter; a positively impelled actuator therefor; a cam synchronized with said reciprocator and operative at each cycle thereof fully to advance said actuator to drive said transmitter positively; and an adjustable limiter mounted coaxially with said cam and engaging the portion of said actuator which also engages said cam for determining the extent of impositive movement of said actuator.

3. A shaper combining a ram; an adjustable-stroke reciprocator therefor; a table; a table-feeding transmission; a one-way motion transmitter; a positively impelled actuator therefor; a rotary cam synchronized with said reciprocator and operative radially at each cycle thereof fully to advance said actuator to drive said transmitter positively; and a normally stationary limiter adjustably mounted coaxial with said cam and adjacent thereto and adapted to engage the portion of said actuator engaged by said cam for adjusting the extent of impositive retreat of said actuator.

4. A shaper combining a ram; an adjustable-stroke reciprocator therefor; a table; a

table-feeding transmission; a one-way motion transmitter; a self-retreating actuator therefor having a cam-engaging portion; a cam synchronized with said reciprocator and operative against said portion at each cycle thereof fully to cock said actuator; and a manually rotatable cam mounted coaxial with the first named cam and adjustable relative thereto and engaging said portion of said actuator for determining the extent of reactive movement of said actuator.

5. A shaper combining a ram; a shaft rotating in synchronism therewith; a rotary cam rotating with said shaft; a normally stationary cam pivoted co-axially with said shaft adjacent said rotary cam and adapted to be turned manually into any one of a series of selective positions; a spring; a plunger reciprocated to and fro periodically by said rotary cam against and with said spring, but having the extent of movement with said spring limited by said normally stationary cam, said plunger having a single end engaging both of said cams; a table; and means for intermittently feeding said table by motion derived from said plunger.

6. A shaper combining a ram; a reciprocator therefor; a table; a table-feeding transmission; a one-way transmitter for intermittently driving said transmission; a plunger adapted to advance to impart motion to said transmitter; a spring for accomplishing each retreat of said plunger; a normally stationary member adapted manually to be shifted into different positions to determine the extent of retreat of said plunger; and an element coaxial with said member and adjacent thereto periodically moving to and fro positively in strokes of invariable lengths and adapted to engage said plunger at the selective station determined by the position of said member and thereupon advance it always to the same advance station, said element serving also to regulate the rate of the impositive retreat of the plunger from said advance station to said selective station.

7. A shaper combining a ram; a shaft rotating in synchronism therewith; a rotary cam rotating with said shaft; a normally stationary cam pivoted co-axially with said shaft and adapted to be turned manually into any one of a series of selective positions; a spring; a plunger having a portion engaging both of said cams reciprocated to and fro periodically by said rotary cam against and with said spring, but having the extent of movement with said spring limited by said normally stationary cam; a table; and a pawl and ratchet-wheel for intermittently feeding said table by motion derived from said plunger.

8. A shaper combining a reciprocating ram; a shaft rotating in synchronism therewith; a rotary cam rotating in invariable synchronism with said shaft; a normally stationary

cam pivoted co-axially with said shaft and adapted to be turned manually into any one of a series of selective positions; a spring; an element longitudinally shifted to and fro periodically by said rotary cam against and with said spring, but having the extent of movement with said spring limited by said normally stationary cam, said element having a portion engaging both of said cams; a table; and means for intermittently feeding said table by motion derived from said element.

In witness whereof I have hereunto subscribed my name.

15 WILLIAM F. ZIMMERMANN.
